UNITED STATES PATENT OFFICE.

JOHN Q. SHERMAN, OF DAYTON, OHIO.

MANIFOLDING DEVICE.

Application filed May 11, 1922. Serial No. 560,237.

To all whom it may concern:

Be it known that I, JOHN Q. SHERMAN, a citizen of the United States, and a resident of Dayton, in the county of Montgomery and State of Ohio, have invented certain new and useful Improvements in Manifolding Devices, of which the following is a full, clear, and exact description, reference being had to the accompanying drawings, forming 10 part of this specification.

My invention relates to manifolding devices wherein the number of webs of paper are imprinted with a like notation, thereby serving as plural forms of the same nature.

15 There are several known ways of forming plural copies in manifolding, one of which is to employ carbon paper between the various webs of paper, so as to transfer the impressions made on the topmost web, and another 20 of which is to employ a ribbon which is disposed in several strands between the webs to be printed.

25 My invention relates to an entirely different mode of forming plural impressions, namely, by employing as the imprinting member, a penetrating device which passes through all of the webs to be marked and is later withdrawn, leaving a like mark on each web.

30 In the embodiment of the invention shown in this application I employ a typewriter of ordinary form and insert between the printing point of the typewriter and the paper support, a chase or carrier which mounts the 35 penetrating devices or pins, these pins being adapted to be given movement by the type on the machine type bars.

In more specific terms, it is my object to provide a writing medium for use with 40 plural webs of paper, which is made up of a mass of independently movable pins, which will be depressed and in composite take the form of any member pressed against the assembly.

45 In connection with a manifolding machine employing a movable typewriter, it is my object to provide means for the installation of such an assembly of pins, same being termed by me the "pin chase," and for the 50 stripping of the paper from the chase and rectifying of the pins ready for another operation.

Also in connection with the pin chase it is my object to provide means for inking the 55 pins and for adjusting the relative tension between pins.

Among other things I show a complete manifolding machine having paper storing and feeding means and special means devised for use with the pin chase method of 60 manifolding for removing the imprinted webs, form after form in sets, as they are used.

These objects and other advantages to be noted I accomplish by that certain construction and arrangement of parts to be herein-after more specifically pointed out and claimed.

In the drawings—

Figure 1 is a detail side elevation and bottom plan view of a pin unit as used by me.

Figure 2 is a top plan view of the chase, chase support and stripper removed from the frame of the machine.

Figure 3 is a side elevation, partly broken away, showing the parts in Figure 2, with a part of the machine frame indicated.

Figure 4 is an enlarged top plan view of a pin assembly such as is used in the case.

Figure 5 is a detail plan view of a corner 80 of the stripper device.

Figure 6 is a perspective view of a complete machine embodying my invention.

Figure 7 is a view showing an enlarged 85 view of the form of printing provided by my invention.

Figure 8 is a detail side elevation and plan of the chase supporting track and elevating device used in the rectifying portion 90 of the machine.

Figure 9 is a detail of a form of type bar and type face preferably used with my novel pin chase.

Figure 10 is a top plan view of the chase support and stripper in their normal relation, this view being taken so as to show the left hand side of the parts illustrated facing downwardly.

Figure 11 is a detail top plan view turned at a right angle to Figure 10, showing the 100 master form and indicator.

Figure 12 is a detail side elevation of the chase, partly broken away to show several of the pins.

Figure 13 is a top plan view of a substitute method of installing paper and rectifying the pins, same being also projected to show an end elevation.

Figure 14 is a detail plan view of the machine with the superimposed parts removed.

Figure 15 is an elevational detail of the chase latch.

Figure 16 is a section of the chase frame. The machine is shown as having a frame 1, which has tracks 2, on which slides the typewriter machine 3. This is the usual form of flat bed machines in which the typewriter support moves for line spacing, and the main body of the typewriter moves for letter spacing. I have not attempted to illustrate this in detail, as it is common practice.

The platen or bed of the machine is indicated at 4, and a rack for mounting a plurality of webs of paper at 5. The paper 6 is fed off from the rolls and along the platen by means of pin wheels 7 energized in the machine illustrated by an electric motor 8. I have not attempted to show in detail the feeding devices for the paper and merely desire to note that I have located the feeding devices behind that portion of the platen on which the manifolding is done, so as to force the paper forward to the printing point. This is not essential, but it brings the feeding devices out of the way of the chase manipulating members and permits the printed copies to be cut off and lifted away when the chase is moved to the rectifying point.

The frame of the machine is formed with walls 9, 9, alongside of the bed, and with a rectifying frame 10 having a bed 11 against which the chase is lowered.

Set into the bed of the machine are a series of four screws 12, the main portions of which lie in countersunk holes in the bed.

Springs 13 are set around the screws in the counter-sunk holes and below the heads of the screws, said springs engaging and pressing toward the heads, the washers 14.

The stripper frame 15 is provided with bifurcated projections 16, which engage over the screws and are pressed upwardly toward the heads by means of the washers. The stripper frame mounts a finely perforated or foraminated screen or plate 17 and the paper is led over the plane beneath this plate.

To mount the pin chase I provide a frame 18 of U-shape with the open side turned toward the rectifying device. This frame provides a track for the chase and is supported over the platen by means of four pins 19, which extend down through holes in the platen.

The chase is formed with a frame 20 provided with rollers 21, 22, on each side, said rollers 21 being placed further from the side of the chase or else made of greater width than the rollers 22. The rollers ride on the short legs of the U-shaped supporting frame, as will be noted from Figure 2.

The rectifying frame is formed with rails 23, which are set so as to form continuations of the short legs of the supporting frame, and the frame wall that confines the

platen of the machine is cut away to permit the chase to slide from the U-shaped frame onto the rails 23.

The rails 23 have notches cut into them into which the rollers of the chase will drop, there being notches 24 to take the rollers 21 and the notches 25 to take the rollers 22.

As shown, each rail 23 is split partially down the center, so as to mount depressible plates 26, which are readily forced down by the chase when it rides on the rails 23. These plates 26 and the pins 19 of the chase supporting frame are both actuated in a like manner to elevate the chase when desired, and at the same time tilt the roller engaging parts, so as to cause the chase to roll by gravity from position over the platen to position in the rectifying frame.

These devices in preferred form are shafts 27, 27, extending beneath the machine and rectifying frames, so as to come under the pins 19 and the ends of the plates 26 respectively. The shafts 27 are connected together in each instance by some sort of a link and lever arm device, as indicated at 28, so that when one of the shafts is operated, the other will be operated also.

The one shaft 27 of each pair has a lever 29 for operating it. The left hand lever 29 operates the shaft assembly for the rectifying device plates, and the right hand one operates the shaft assembly for the pins 19 of the chase supporting frame.

On each of the shafts 27 are small cams 30 which engage the plates 26 or pins 19 as the case may be, and there force them up. In practice the cams 30 on the far sides of the supporting frame and the rectifying frame are of greater size or pitch than the ones at the adjacent portions of said members, so that when the lever 29 for the supporting frame is rocked, the frame will be lifted away from the platen carrying the chase with it, and will at the same time be tilted toward the rectifying frame rails 23. The operation of the lever for the rectifying frame will force up the lifting plates 26, and thus press up on the rollers 22 of the chase frame, thereby lifting the rolls from the notches in the rails, and at the same time 115 tilting the chase toward the supporting frame.

The chase frame is formed with one side bar at least channeled out as at 30^a, and a piece 31 is set in this channel and held in adjustment by means of abutment screws 32 held in the said side bar. By turning down the screws, the piece 31 may be forced inwardly of the frame, thereby controlling the space confined thereby.

On the lower portion of the chase frame I mount a screen or finely perforated or foraminated plate 33, against which I place a pad of felt 34, and on the base of the felt 34 I place another like screen or foraminated

plate 35. These screens are arranged so that they bear special relation to the pin devices held in the chase. The rear edge of the chase may have a paper cutting knife 5 35^a.

The pins in preferred form are made of sufficient fineness to serve the desired purpose, the showing in Figures 1, 4, and 12 being considerably enlarged. They have 10 preferably cylindrical or octagonal shanks A, and points B having a taper which will pass only partially through the holes in the screens. Thus when arranged ready for printing, the pins will have their points 15 flush with the bottom screen, and the taper will be such that after a depression of any pin far enough to make the desired imprint; the upper screen will engage the pin between the point and its largest diameter and hold 20 it from further downward movement.

With the pins being cylindrical and the most convenient form of the chase being square, the result will be an arrangement of the pins in the pattern indicated in Figure 4. The adjustment of the chase serves 25 to give the desired rigidity to the pin pack, but when using the cylindrical shank for the pins, each pin will only have a four line contact with the other pins, so that the tendency for one pin to drag the others will 30 be negligible.

The preferred form of type used on the type bars of the typewriter has been illustrated in Figure 9, wherein the base of 35 the type piece, as at 36, has the letter 37 (A) formed in a considerably elevated manner rather more pronounced than in the usual typewriter, and also preferably thinner than the contact ends of the pins, so as to 40 procure the finest possible printing or lineation.

In operation, the device is used as follows: The operator having set his stripper plate in position, leaves it there, since it 45 works automatically. He feeds a plurality of webs of paper along the platen beneath the stripper during the period when it is raised by means of the springs and washers on the mounting screws. The chase, having 50 the pin assembly therein properly tensioned, is set on the supporting frame, which is at that time in elevated position by reason of its mounting pins being raised. The supporting frame is then lowered and the typewriter drawn over the chase ready for writing.

Writing is done in the usual manner and each type face will press down an assembly 55 of pins, following the outlines of the type face, with the result of forming a perforation by the pins struck down, as shown in Figure 7, wherein the perforations are arranged to make the letters JQS. The showing in Figure 7 is enlarged over the preferred size of type used with a typewriter.

The pins have preferably their tapered points formed in a number of veins 14^a which act as an ink space, thereby enabling the points to readily carry on their surface sufficient ink from the pad between the two 70 mounting screens to mark in ink the outlines of each perforation on all superimposed paper webs.

As many webs of paper as desired are 75 passed under the stripper screen, since I have found that the pins will clearly mark as many webs of paper as the pin points will penetrate, which is naturally quite large.

The typewriter is thus operated as usual, and the chase is made large enough to provide a printing medium for the full sized form which it is desired to fill in, or the letter which it is desired to write.

When the writing is finished, the typewriter is moved away and the lever 29 for the supporting frame is thrown down against its stop 29^a, whereupon the chase will be raised while the stripper plate prevents the paper from being pulled up as 90 the pins are withdrawn from it. The stripper plate rises only enough to permit paper to pass under it and does not follow the supporting frame.

When the frame is raised, the chase will 95 be tilted toward the rectifying device and will move of itself or can be pushed toward the said device, so that it rides on the rails 23 and forces down the elevating plates 26. The rollers of the chase will drop into 100 the notches 24 in the rails 23, when the chase is entirely over the rectifying bed, there dropping the pins that project from the lower screen of the chase against the bed and forcing them back to normal position.

I provide a heavy hinged plate 40 hinged above the rectifying bed and held in open position by a stop 41. This plate may be lowered until its studs 42 at the free end 110 thereof contact with stops 43, on the platen frame. This will permit the plate to come down over the top of the pin assembly without such force as to blunt any of the pins and will give a further movement to any 115 pin which has been forced out of a true level at the upper face of the assembly.

A roller, operated over the chase, would effect the same result.

The operator at this time pulls out the 120 paper which has been printed and feeds in a new supply beneath the stripper. He then lowers the lever 29 for the plates 26 and thereby raises these plates, lifts the chase out of the notches and gravitates it 125 back toward the supporting frame, ready for another printing operation.

I will provide some sort of latch to hold the chase fast during printing. This may be in the form of a dog 44, pivotally held 130

on a bracket 45 on the machine frame and adapted to engage in a socket 46 in the chase frame. The dog is spring-pressed and faced so as to snap into engagement with 5 the chase, and carries a lug 47 on its under side which rests on the supporting frame. Thus when the supporting frame is raised, the lug is pressed up by the supporting frame and the outer end of the dog thus 10 moved out of the chase socket.

Any other form of latch could be provided, the above being merely one form, which releases automatically.

It will be noted that I do away with 15 carbon paper entirely and that I form an impression which is well inked around each tiny hole. The fact that the pins stay in depressed position while the entire written operation is being performed tends to insure 20 also that a fully outlined penetration will be made.

As giving the operator a guide in printing, and avoiding the necessity of bringing one web of paper over the top of the chase, 25 I provide a master plate 50 on the side of the machine frame on which is arranged one of the forms that is to be filled out. An arrow 51, mounted on the carriage of the typewriter and thus moving with it, passes 30 over the master form, thereby giving the operator an absolute guide as to where each letter will appear on the printed forms beneath.

When used for writing multiple letters or 35 the like, I find that a piece of thin paper laid over the chase and held in any desired way does not interfere with the full operation of the pins. This web of paper is not to be preserved, since it will be in the form 40 of a stencil when the writing is completed. A master stencil could also be transferred to the top of the pins by painting it on the tops of the pins. Except for use with ruled paper no master is necessary, since the top 45 of the chase is perfectly legible.

As an alternative method of feeding paper into the machine and providing for rectifying the pins, I provide in the framework of the machine instead of a fixed 50 platen, a movable platen, which is made up of a plate 60 and a printing platen plate 61 of material that will not blunt the pins. The forms 62 to be written on are collated over the portion 61 and held in place, for 55 example, by pins 63.

The forms are set in place individually or in sets on the pins, and the platen pushed into the frame on a shoulder provided for this purpose. This will bring the paper 60 under the stripper and will move the steel plate out of the way.

After the web has been written upon, the chase will be lifted and the platen pulled out, exposing the printed web, and bringing 65 the plate under the pins. The operator will

then drop the chase against the plate, which will bring the pins into line with the tops on a plane surface. The chase will then be lifted, the platen bearing new forms will be returned to writing position, and the chase 70 lowered for writing purposes.

There are many ways in which the pin assembly device may be employed for making plural copies, and in this application I have merely attempted to describe one form 75 of machine which will readily employ the device.

Having thus described my invention, what I claim as new and desire to secure by Letters Patent, is:

1. A means for printing plural copies, which comprises an assembly of pins having independent movement, means for holding the pins together so as to permit of the depression of selected pins to penetrate the 85 plural copies, and means for applying ink to the pins prior to their penetration of the plural copies.

2. A printing device for plural copies, comprising an assembly of pins, means for holding them together, so as to permit the individual pins to be depressed, said pins preferably having cylindrical shanks, and paper penetrating points, and means for applying ink to the penetrating portions of 95 the pins prior to their penetration of the plural copies.

3. A pin chase for the purpose described, comprising in combination, a frame, a mass of pins arranged parallel with each other 100 and abutting each other within the frame, said mass being held in the frame so as to permit individual movement of selected pins, and ink carrying means held in position with regard to the chase, said pins being 105 arranged adapted to penetrate a plurality of sheets of paper after having passed through said ink carrying means.

4. A pin chase for the purpose described, comprising, in combination, a frame, a mass of pins arranged parallel with each other 110 and abutting each other in the frame, said pins being held in the frame so as to permit individual movement of selected pins, said pins having their penetrating point portions 115 formed with ink carrying pockets, and means carried with the chase through which the pins must pass when moved, said means including a penetrable inking pad.

5. A pin chase for the purpose described, comprising, in combination, a frame, a mass of pins arranged parallel with each other within the frame, with the heads of the pins only exposed at the one opening of the frame, and the other opening of the frame 125 having a foraminated closure through which the points of the pins pass, said pins being held in the frame so as to permit selected pins to be moved individually, for the purpose described, said foraminated closure in- 130

cluding a metallic member and a penetrable inking pad held in place thereby on the chase.

6. A pin chase for the purpose described, comprising, in combination, a frame, a mass of pins arranged parallel with each other and abutting each other in the frame, said pins being held in the frame so as to permit individual movement of selected pins, said pins having their pointed ends formed with ink carrying pockets, and means carried with the chase through which the pins must pass when moved, said means comprising a penetrable inking pad and foraminated sheets on both faces thereof, said pad and sheets being attached to the chase.

7. In a flat bed manifolding device, the combination with a platen on which plural sheets of paper are to be arranged, a pin chase of the character described, means for retaining the chase over the platen, and a typewriting machine having keys with elevated type faces movable to operate in positions over said chase.

8. In a flat bed manifolding device, the combination with a platen on which plural sheets of paper are to be arranged, a pin chase of the character described, means for retaining the chase over the platen, and a typewriting machine movable to operate in positions over said chase, a master sheet retaining means located at the side of the platen, and an indicator movable with the typewriter located over the said retaining means.

9. In a flat bed manifolding device, the combination with a platen on which plural sheets of paper are to be arranged, a pin chase of the character described, rails on which said chase is adapted to move, said rails being provided with a device for elevating them to lift the chase and a rectifying device for returning depressed pins to normal position in the chase, said device having rails to receive the chase from the first mentioned rails and including a flat bed against which the chase is lowered.

10. In a flat bed manifolding device, the combination with a platen on which plural sheets of paper are to be arranged, a pin chase of the character described, means for retaining the chase over the platen, and a typewriting machine movable to positions for writing over said chase, said chase retaining means being adapted to be lifted to remove the pins thereof from the paper.

11. In a flat bed manifolding device, the combination with a platen on which plural sheets of paper are to be arranged, a pin chase of the character described, means for retaining the chase over the platen, and a typewriting machine movable to positions for writing over said chase, said chase retaining means being adapted to be lifted to remove the pins thereof from the paper,

and a foraminated stripper plate mounted over the platen between it and the pin chase.

12. In a flat bed manifolding device, the combination with a platen on which plural sheets of paper are to be arranged, a pin chase of the character described, means for retaining the chase over the platen, and a typewriting machine movable to positions for writing over said chase, said chase retaining means being adapted to be lifted to remove the pins thereof from the paper, and a foraminated stripper plate mounted over the platen between it and the pin chase, said stripper plate having resilient mounting means tending to move it away from the paper when the chase is lifted.

13. In a device of the character described, a platen on which plural sheets of paper are to be arranged, a plurality of posts, a stripper screen or the like arranged on the posts, resilient means on the posts to hold the screen away from the paper, a chase supporting frame, means for raising and lowering it with relation to the screen and a pin chase of the character described mounted on the frame.

14. In combination, a platen, a rectifying device, including a flat plate, a supporting frame mounted over the platen, means for elevating the frame and tilting it toward the rectifying device, and rails in the rectifying device, a pin chase of the character described, and rollers or the like on the chase adapted to engage on the frame and the rails, said frame and rails being arranged so that the chase will roll from the one to the other, and means for lowering and raising the chase on the rails, said rails passing across the said flat plate.

15. In combination, a platen, a rectifying device, including a flat plate, a supporting frame mounted over the platen, means for elevating the frame and tilting it toward the rectifying device, and rails in the rectifying device, a pin chase of the character described, and rollers or the like on the chase adapted to engage on the frame and the rails, said frame and rails being arranged so that the chase will roll from the one to the other, and means for lowering and raising the chase on the rails, said rails passing across the said flat plate, and a hinged plate adapted to come down over the top of the chase and engage the pins therein when the chase is lowered to a position of engagement with the flat plate.

16. A rectifying device for machines having a pin chase of the character described, said device comprising a flat plate, rails on which the chase will move across said plate, means for lowering the chase until the pins contact with the plate, and a movable upper plate having a fixed limit of movement, said plate being adapted to come down over the upper ends of the pins in the chase when

the points thereof are in contact with the flat plate first above noted.

17. A means for printing plural copies, which comprises an assembly of pins having independent movement, means for holding the pins together, and means for depressing selected pins to penetrate the plural copies, and means for applying ink to the pins, a frame, and means thereon to support a typewriter, the pin assembly and plural sheets of paper.

18. In a flat bed manifolding device, the combination with a platen on which plural sheets of paper are to be arranged, a pin chase of the character described, means for

retaining the chase over the platen, and a typewriter machine movable to operate in positions over said chase, and means for rectifying the pins in the chase.

19. A pin chase for the purpose described, comprising, in combination, a frame, a mass of pins arranged parallel with each other and abutting each other in the frame, said pins being held in the frame so as to permit individual movement of selected pins, means for supporting the said chase, and a paper platen positioned under the said chase, and a typewriter movable to positions over the said chase.

JOHN Q. SHERMAN.
